SEPARATION AND PURIFICATION OF AROMATIC AND NON-AROMATIC NITROGEN BASES

James R. Bailey, Austin, Tex., assignor to Union Oil Company of California, Los Angeles, Calif., a corporation of California

No Drawing. Application October 17, 1932,
Serial No. 638,195

14 Claims. (Cl. 260—38)

This invention relates to a process for the resolution of complex mixtures of nitrogen bases. More specifically it relates to a process for the resolution of complex mixtures of nitrogen bases such as may be extracted from natural sources, for instance petroleum oils (including the asphaltic type California oils), shale, or the pyrolytic distillates of cottonseed meal, into aromatic and hydroaromatic nitrogen bases. This invention is 10 a continuation, in part, of my application Serial No. 590,913, filed Feb. 4, 1932.

As a general rule, a crude mixture of nitrogen bases, extracted from any of the sources previously referred to consists of bases which may be classified as aromatic and hydroaromatic, or naphthenic bases. One of the fundamental differences between the aromatic and the hydroaromatic nitrogen bases lies in their respective refractive indices. The hydroaromatic nitrogen bases exhibit a much lower refractive index than the aromatic ones. Thus, for instance, quinoline, isoquinoline and their homologues exhibit a refractive index of approximately 1.600 (based upon the D line of the sodium spectrum, observation made at 25° C.) while the hydroaromatic nitrogen bases possess refractive indices ranging from 1.4833—1.5129 under the same conditions. Therefore, the determination of refractive indices is of great help to determine the completeness of 20 the separation of a mixture of nitrogen bases into aromatic and hydroaromatic bases.

A typical nitrogen base, illustrative of the aromatic type, is 2,3,8 trimethylquinoline, while the hydroaromatic type may be illustrated by the pyridine base $C_{16}H_{25}N$ which is generally considered to have the following structure:

and which may be considered as a piperidine derivative. In the aforesaid application, I have indicated that the 2,3,8 trimethylquinoline may

be separated as an insoluble acid sulphate from the soluble acid sulphate of the $C_{16}H_{25}N$ base, both bases being concentrated in a fraction of nitrogen bases boiling at about 276° C., the fraction having been extracted with liquid sulphur dioxide from a California kerosene, produced from a McKittrick type crude oil. I have discovered that the method of separating the aromatic 2,3,8 trimethylquinoline from the hydroaromatic $C_{16}H_{25}N$, is universally applicable to, and extremely efficient in the removal of admixed hydroaromatic bases from aromatic nitrogen bases present in any crude mixture of these two types of bases. The method referred to above is also extremely helpful in removing the hydroaromatic 15 nitrogen bases remaining admixed with the aromatic nitrogen bases after a preliminary separation of the nitrogen bases as to types has been carried out by some other method. A number of processes for the complete or partial separation 20 of mixtures of nitrogen bases into aromatic and hydroaromatic bases have been disclosed and claimed in my copending application Serial No. 627,134.

It is, therefore, an object of my invention to 25 provide a simple and efficient method of resolving a complex mixture of nitrogen bases into fractions comprising only aromatic or hydroaromatic nitrogen bases.

Briefly stated, my invention comprises a process 30 for the resolution of mixtures of nitrogen bases of variable complexity into aromatic and hydroaromatic bases by the formation of the acid sulphates of the bases and their separation by means of water soluble organic solvents in which 35 the acid sulphates of the aromatic bases are substantially insoluble and the acids sulphates of the hydroaromatic bases are readily soluble. Examples of such solvents are ketones, for instance acetone, alcohols, for instance ethyl or methyl 40 alcohol and esters, for instance ethyl acetate.

My invention also comprises any of the specific procedures hereinafter disclosed.

In order to resolve a mixture of nitrogen bases into aromatic and hydroaromatic bases, it is necessary to isolate the bases from the medium in which they are present. Thus, in the case of mixtures of bases present in petroleum distillates, it is necessary to remove the bases from their oil content. There are several methods by which 50

this can be accomplished. For instance, the nitrogen bases may be extracted from the petroleum distillates by repeated washing with dilute sulphuric acid. Another method of extracting 5 the nitrogen bases from petroleum distillate consists in extracting them with liquid sulphur dioxide according to the well known Edeleanu process (U. S. Patent 911,553). The extract phase thus obtained, contains large amounts of liquid 10 sulphur dioxide, the nitrogen bases and the SO_2 soluble hydrocarbons present in the distillate. The major portion of the sulphur dioxide is then vaporized from the extract phase. The "extract" 15 remaining after the major portion of the sulphur dioxide has been removed, contains in addition to small amounts of dissolved sulphur dioxide, a much higher concentration of nitrogen bases (partly as sulphur dioxide addition compounds, partly as free nitrogen bases) than was present 20 in the original crude distillate. This extract is then treated with dilute sulphuric acid or water for instance on countercurrent contact to extract the bases as acid sulphates or as acid sulphites 25 in aqueous solution and the free nitrogen bases are obtained as a crude mixture by the addition of an inorganic base to the aqueous solution referred to above. These processes of extracting a 30 mixture of nitrogen bases from natural sources have been fully disclosed and claimed in my co-pending application Serial No. 590,913 of which this application is a continuation in part.

My preferred method for resolving a mixture of nitrogen bases into aromatic and hydroaromatic bases is as follows:

35 A mixture of nitrogen bases, such as may be extracted from any of the natural sources referred to earlier in this specification, is dissolved in about twice its volume of acetone or alcohol. Concentrated sulphuric acid (sp. gr. 1.84) is then 40 added slowly to the solution to precipitate substantially all of the aromatic nitrogen bases as insoluble acid sulphates which come down either in the form of a white crystalline precipitate or in the form of a white to yellow oily smear. 45 When the aromatic bases are present in much larger proportions than the hydroaromatic, and this aromatic material consists of only two or three individual bases, the precipitate tends to be crystalline, but unless these conditions exist, 50 it is oily. The acid sulphates of the hydroaromatic bases remain for the most part dissolved in the acetone or alcohol.

The amount of sulphuric acid required to quantitatively salify a given weight of a mixture of 55 nitrogen bases is readily calculated from the nitrogen content of the latter. For instance, 100 grams of a mixture of nitrogen bases, which on analysis showed to contain 7% of nitrogen, would require approximately 51.58 grams of 95% sulphuric acid for conversion to acid sulphates. The most efficient conversion of the bases into acid sulphates is brought about by the addition of an equal molecular quantity of sulphuric acid as 60 illustrated by the above figures. It has been observed that the weight of the insoluble acid sulphates increases at first with the amount of sulphuric acid added until a limit is reached, the 65 limit being slightly less than an equal molecular quantity of sulphuric acid. After the limit has been reached, any subsequent addition of sulphuric acid tends to dissolve some of the precipitated acid sulphates. The fraction of the precipitate redissolving is principally composed of hydroaromatic acid sulphates which were at first 70

precipitated together with the aromatic acid sulphates. Consequently, the precipitated acid sulphates contain a higher concentration of aromatic nitrogen bases when the volume of acid used per volume of base is increased. However, as 5 previously stated, a very efficient precipitation, i. e. one in which the precipitates contain a high concentration of aromatic nitrogen bases may be carried out by using equal molecular quantities of sulphuric acid and nitrogen bases. The 10 reaction mixture should be kept reasonably cool to prevent the formation of mesitylene or ether, due to a reaction between the sulphuric acid and the acetone or alcohol. It has been found desirable to add the sulphuric acid rather slowly as 15 sometimes on a more rapid addition of the sulphuric acid, a carbonization of the nitrogen bases was observed. After all of the sulphuric acid has been added, the reaction mixture is cooled somewhat further, the insoluble acid sulphates of the 20 aromatic nitrogen bases filtered off and the filter cake washed with a little acetone or alcohol to remove any of the remaining acid sulphates of the hydroaromatic nitrogen bases.

As a modification of the foregoing process, I 25 may operate as follows: A mixture of nitrogen bases, extracted from a California kerosene with liquid sulphur dioxide in the manner outlined earlier in this specification, or from any of the 30 sources previously referred to and containing both aromatic and hydroaromatic bases, is commingled with an equivalent of concentrated sulphuric acid which is slowly added to the solution at reduced temperatures. The acid sulphates of 35 the nitrogen bases are then digested with acetone or alcohol in either of which the acid sulphates of the aromatic bases are difficultly soluble but in which the hydroaromatic acid sulphates are soluble to a considerable degree. The hydroaromatic acid sulphates tend to accumulate in the 40 solvent while the white acid sulphates of the aromatic bases settle out from the solution as a precipitate or as an oily smear depending upon the 45 concentration of aromatic bases as stated above.

The insoluble acid sulphates of the aromatic bases may be treated with an excess of caustic soda to liberate the free bases or they may be separated by fractional crystallization from appropriate solvents, or the sulphates may be directly converted to other salts, such as picrates, 50 by the addition of an alcoholic solution of picric acid and the picrates of the bases separated by fractional crystallization from alcohol or other solvents. In closely cut distillation fractions, especially those fractions obtained by fractionally 55 distilling a crude mixture of nitrogen bases extracted from a California kerosene, there are usually not more than 2 or 3 aromatic nitrogen bases present. After these bases have been freed from the admixed hydroaromatic bases, fractional crystallization as salts from appropriate solvents, such as outlined above, leads to the isolation of single compounds in a number of instances.

The hydroaromatic bases may be recovered as 65 free bases by distilling off the solvent from the acetone or alcohol solution of the acid sulphates and adding sodium hydroxide or ammonium hydroxide to the acid sulphates remaining as a 70 residue.

The addition of the sulphuric acid to any mixture of nitrogen bases obtained from petroleum (including the California asphaltic petroleums) shale or from a pyrolytic distillation of cotton- 75

seed meal, may also be carried out fractionally. In fractionally precipitating the acid sulphates of the nitrogen bases or of any fraction thereof, the bases are dissolved in the appropriate amount 5 of solvent, such as acetone or alcohol, small portions of concentrated sulphuric acid are added while cooling the mixture, and the precipitates, consisting chiefly of aromatic acid sulphates, are withdrawn after each addition of sulphuric acid.

10 In addition, my process may operate as an aid in separating a pure nitrogen base from a fraction of nitrogen bases.

The completeness of the separation of the aromatic bases from the hydroaromatic ones by 15 my process, may be ascertained by measuring the decrease or increase in refractive index of the mixture. The removal of the aromatic bases from a mixture containing aromatic and hydroaromatic bases will tend to decrease the refractive index of the mixture and will indicate to an operator the extent of separation at any stage 20 of the process.

The following example is given by way of illustration:

25 A fraction of nitrogen bases boiling at approximately 285° C. was obtained by fractionally distilling under reduced pressure a crude mixture of nitrogen bases extracted from a crude California kerosene by the liquid sulphur dioxide extraction process referred to earlier in this specification.

30 A sample of this fraction weighing 152 grams and having a refractive index, n 30/D=1.5395, was dissolved in twice its volume of acetone and 35 52 c. c. of concentrated sulphuric acid was added while cooling and stirring the mixture. A voluminous white precipitate of acid sulphates, weighing 37.857 grams was formed. The acid sulphates were then filtered off, washed with 30 c. c. of acetone and dried at 110° C. The bases were liberated from the acid sulphates in the usual manner by the addition of caustic soda. They weighed 21.8 grams and had a refractive index of n 30/D=1.5886. The residual bases remaining dissolved in the acetone as acid sulphates, after distilling off the acetone, were taken up in water and the bases freed with ammonium hydroxide. They weighed 128.2 grams and had a refractive index of n 30/D=1.5262. The aromatic nitrogen bases separated as acid sulphates from this fraction form picrates on the addition of picric acid to them. These picrates recrystallize very nicely from 95% ethyl alcohol. The advantage of the picrate recrystallization from ethyl alcohol lies in the fact that the picrates of the aromatic bases are much more insoluble than the picrates of the hydroaromatic bases, so that a further purification may be brought about by retaining in the solution some of the dissolved picrates of the hydroaromatic bases and precipitating the insoluble picrates of the aromatic nitrogen bases.

60 As stated earlier in this invention, the amount of the sulphuric acid added in the separation of the aromatic from the hydroaromatic bases is of importance.

65 The following example is illustrative of the influence of the amount of sulphuric acid added and at the same time indicates how my process may operate as an aid in isolating a pure nitrogen base from a fraction of nitrogen bases having a narrow boiling point range.

70 A fraction of nitrogen bases boiling at approximately 275° C. was obtained by fractionally dis-

tilling under reduced pressure a mixture of nitrogen bases extracted from a California kerosene according to the process outlined earlier in this specification. This fraction, having a refractive index n 60/D=1.5155, contains considerable 5 amounts of 2,3,8 trimethylquinoline

10

(refractive index n 60/D=1.5828) and a hydro- 15 aromatic base $C_{16}H_{25}N$

20

25

(refractive index n 60/D=1.4588).

30 Sample of this fraction of 100 c. c. each were dissolved in either alcohol or acetone and varying amounts of 95% sulphuric acid were added while cooling the solution. The sulphates in each case were weighed and the refractive indices of the bases freed from these sulphates taken. The results are shown in the following table:

35

Table I

c. c. of bases	c. c. of H_2SO_4	Grams of acid sulphates	n 60/D of free bases
100	22	46.5	1.5220
100	23	34.1	1.5568
100	26	24.4	1.5648

40

45 The results, as shown in this table, indicate that with the smaller amount of sulphuric acid added, a greater weight of insoluble acid sulphates is obtained (which is due to the precipitation of some of the hydroaromatic bases as acid sulphates) and that when a limit is reached 50 (which in this specific example seems to be between 22 and 23 c. c. of sulphuric acid) the hydroaromatic acid sulphates tend to go into solution decreasing the weight of the insoluble acid sulphates but increasing the refractive index due 55 to a higher concentration of aromatic bases in the specific precipitates. The latter were removed, in great part, without liberating the bases from the acid sulphates by extraction of the hydroaromatic acid sulphates with boiling acetone. 60 The insoluble acid sulphates after recrystallization from alcohol yielded bases with a refractive index of approximately 1.5800 at 25° C.

50

75

The pure 2,3,8 trimethylquinoline, referred to above, may be obtained by treating the acid sulphates of the bases having refractive indices of 1.5568 and 1.5648 (see Table I) or the nitrogen bases having a refractive index of 1.5800 obtained as outlined above, with picric acid which, on simple addition to the acid sulphates (both the picric acid and the acid sulphates being preferably dissolved in alcohol) forms the picrates of the bases present. The picrate of 2,3,8 trimethylquinoline being far less soluble in alcohol than the accompanying picrates of the hydroaro-

matic or other aromatic bases, is easily isolated by fractional recrystallization from alcohol and the free base obtained by addition of an inorganic base such as sodium hydroxide or ammonium hydroxide to the picrate.

The free 2,3,8 trimethylquinoline is an important dye intermediate. An extremely fast yellow dye of a brilliant color may be derived from this methylated quinoline by simply condensing the same with phthalic anhydride at a temperature of 200° C. The manufacture of this phthalone dye as well as phthalone dyes which may be prepared from any fractions of methylated quinolines which may be obtained from a mixture of nitrogen bases by the process outlined in this invention are disclosed and claimed in my copending application Serial No. 628,770.

The following specific example will illustrate how an individual aromatic nitrogen base may be isolated from admixed hydroaromatic bases by the process herein disclosed:

A mixture of nitrogen bases extracted from a California kerosene by the liquid sulphur dioxide process outlined earlier in this specification was carefully fractionally distilled under reduced pressure and a fraction boiling at approximately 247-253° C. (atmospheric pressure) collected.

A portion of this fraction, weighing about 100 grams, was dissolved in twice its volume of acetone and 50 c. c. of concentrated sulphuric acid (sp. gr. 1.84) was slowly added to the solution which had been cooled to below 50° F. The aromatic base 2,8 dimethylquinoline which is practically the only aromatic base present in this fraction precipitated as a white to yellow crystalline acid sulphate, while the hydroaromatic bases present in this fraction remained in solution. The precipitate was washed with a little acetone to remove any remaining acid sulphates of the hydroaromatic nitrogen bases and then dried at a temperature slightly above the boiling point of water. The free nitrogen base was obtained by adding an inorganic base such as sodium hydroxide to the acid sulphate. The total yield of 2,8 dimethylquinoline was about 10% of the original weight of bases used. The boiling point of the base was 253° C. and it was characterized by a fecal odor. This quinoline also is a useful intermediate for manufacturing quinphthalone dyes.

In order to distinguish between the aromatic quinolines and substituted quinolines the acid sulphates of which are insoluble in my organic solvents and those bases yielding soluble acid sulphates, I have chosen to call the latter type of bases "hydroaromatic bases".

The bases yielding soluble acid sulphates are not completely hydrogenated in the same manner as piperidine or coniine which is evidenced by the fact that they are not susceptible to dehydrogenation (see Bailey, et al. Jour. Chem. Soc. 55, 4145, 1933), but for want of a better term and in view of the fact that the identity of the bases yielding soluble acid sulphates has not yet been fully established I have labeled them as hydroaromatic.

The examples disclosed in this invention are not to be considered as limitations imposed thereon but are merely illustrative of the generic invention and many variations may be made within the scope of the appended claims.

I claim:

1. A process for resolving a mixture of organic nitrogen bases containing aromatic and non-aromatic nitrogen bases, as derived from petroleum, shale and pyrolytic distillates of cot-

tonseed oil, and which comprises dissolving said mixture of nitrogen bases in an inert organic solvent, adding sulphuric acid to the solution to form insoluble acid sulphates of the aromatic bases and soluble acid sulphates of the non-aromatic bases and separating insoluble acid sulphates of the aromatic bases from the soluble acid sulphates of the non-aromatic bases.

2. A process for resolving a mixture of organic nitrogen bases containing aromatic and non-aromatic nitrogen bases, as derived from petroleum, shale and pyrolytic distillates of cottonseed oil, and which comprises dissolving said mixture in acetone, adding sulphuric acid to the solution to form insoluble acid sulphates of the aromatic bases and soluble acid sulphates of the non-aromatic bases and separating the insoluble acid sulphates of the aromatic bases from the acetone solution containing chiefly dissolved acid sulphates of the non-aromatic bases.

3. A process for resolving a mixture of organic nitrogen bases containing aromatic and non-aromatic nitrogen bases, as derived from petroleum, shale and pyrolytic distillates of cottonseed oil, and which comprises dissolving said mixture in alcohol, adding sulphuric acid to the solution to form insoluble acid sulphates of the aromatic bases and soluble acid sulphates of the non-aromatic bases and separating the insoluble acid sulphates of the aromatic bases from the alcohol solution containing chiefly dissolved acid sulphates of the non-aromatic bases.

4. A process for resolving a mixture of organic nitrogen bases containing aromatic and non-aromatic nitrogen bases, as derived from petroleum, shale and pyrolytic distillates of cottonseed oil, and which comprises dissolving said mixture in alcohol, adding successive small portions of sulphuric acid to the solution to precipitate fractions of the aromatic bases as acid sulphates leaving the acid sulphates of the non-aromatic bases dissolved in the alcohol, withdrawing insoluble acid sulphates of the aromatic nitrogen bases after each addition of sulphuric acid and continuing the addition of sulphuric acid to the solution until no more insoluble acid sulphates of the aromatic bases are formed.

5. A process for obtaining an aggregate of aromatic nitrogen bases free from non-aromatic bases and an aggregate of non-aromatic bases free from aromatic bases which comprises extracting a mixture of nitrogen bases from a petroleum distillate containing the same, dissolving said mixture in an inert organic solvent, adding sulphuric acid to the solution to precipitate substantially all of the aromatic nitrogen bases as insoluble acid sulphates while the acid sulphates of the non-aromatic bases remain in solution, separating insoluble acid sulphates of the aromatic nitrogen bases and recovering the acid sulphates of the non-aromatic bases by vaporizing the solvent.

6. A process for obtaining an aggregate of aromatic nitrogen bases free from non-aromatic bases and an aggregate of non-aromatic bases free from aromatic bases which comprises extracting a mixture of nitrogen bases from a petroleum distillate containing the same, dissolving said mixture in alcohol, adding sulphuric acid to the solution which has been cooled to below 15° C. to precipitate substantially all of the aromatic nitrogen bases as insoluble acid sulphates while the acid sulphates of the non-aromatic bases remain in solution, separating insoluble acid sulphates of the aromatic nitrogen bases and

recovering the acid sulphates of the non-aromatic bases by vaporizing the solvent.

7. A process for obtaining an aggregate of aromatic nitrogen bases free from non-aromatic bases, and an aggregate of non-aromatic bases free from aromatic bases, which comprises extracting a mixture of nitrogen bases from a petroleum distillate containing the same, dissolving said mixture in acetone, adding sulphuric acid to the solution to precipitate substantially all of the aromatic nitrogen bases as insoluble acid sulphates while the acid sulphates of the non-aromatic bases remain in solution, separating insoluble acid sulphates of the aromatic nitrogen bases and recovering the acid sulphates of the non-aromatic bases by vaporizing the acetone from the solution.

8. A process for obtaining an aggregate of aromatic nitrogen bases free from non-aromatic bases and an aggregate of non-aromatic bases free from aromatic bases which comprises extracting a California kerosene, distilled from a asphalt base crude oil, with liquid sulphur dioxide to obtain an extract phase containing large amounts of liquid sulphur dioxide, the nitrogen bases present in the kerosene distillate together with the sulphur dioxide soluble portion thereof, vaporizing the major portion of the sulphur dioxide, commingling the extract so obtained, with water to obtain an aqueous solution of the acid sulphites of the nitrogen bases, adding an inorganic base to the said aqueous solution to isolate a crude mixture of nitrogen bases, containing aromatic and non-aromatic nitrogen bases, dissolving this mixture in acetone, adding sulphuric acid to the solution, in an amount sufficient to precipitate substantially all of the acid sulphates of the aromatic nitrogen bases present in the mixture while the acid sulphates of the non-aromatic bases remain in solution and separating the insoluble acid sulphates of the aromatic nitrogen bases from the acetone solution containing substantially only dissolved acid sulphates of the non-aromatic nitrogen bases.

45. 9. A process for obtaining an aggregate of aromatic nitrogen bases free from non-aromatic bases and an aggregate of non-aromatic bases free from aromatic bases which comprises extracting a California kerosene, distilled from an asphalt base crude oil, with liquid sulphur dioxide to obtain an extract phase containing large amounts of liquid sulphur dioxide, the nitrogen bases present in the kerosene distillate together with the sulphur dioxide soluble portion thereof, vaporizing the major portion of the sulphur dioxide, commingling the extract so obtained with water to obtain an aqueous solution of the acid sulphites of the nitrogen bases, adding an inorganic base to the said aqueous solution to isolate a crude mixture of nitrogen bases, containing aromatic and non-aromatic nitrogen bases, dissolving this mixture in alcohol, adding sulphuric acid to the solution, in an amount sufficient to precipitate substantially all of the acid sulphates of the aromatic nitrogen bases present in the mixture while the acid sulphates of the non-aromatic bases remain in solution and separating the insoluble acid sulphates

of the aromatic nitrogen bases from the alcohol solution containing substantially only dissolved acid sulphates of the non-aromatic nitrogen bases.

10. A process for obtaining 2,3,8 trimethylquinoline which comprises extracting by means of liquid sulphur dioxide a mixture of nitrogen bases from a kerosene distillate produced from an asphalt base crude oil, eliminating sulphur dioxide, extracting with water, isolating a mixture of nitrogen bases with an inorganic base, fractionally distilling said mixture of bases under reduced pressure to isolate a fraction boiling between 275 to 277° C. (atmospheric pressure), dissolving said fraction in alcohol, adding successive small portions of sulphuric acid to the alcohol solution to form an alcohol insoluble acid sulphate of the 2,3,8 trimethylquinoline present in the aforementioned fraction, separating the insoluble acid sulphate of the said quinoline from the alcohol solution as a white crystalline solid after each addition of sulphuric acid, adding an alcoholic solution of picric acid to the said insoluble acid sulphate to precipitate a substantially pure 2,3,8 trimethylquinoline picrate and recovering the free base from the picrate by addition of an inorganic hydroxide.

11. A process for obtaining 2,8 dimethylquinoline, which comprises extracting a mixture of nitrogen bases from a kerosene distillate produced from an asphalt base crude oil, fractionally distilling said mixture under reduced pressure and collecting a fraction boiling from 247-253° C. (atmospheric pressure), cooling said fraction below 15° C., dissolving said fraction which contains a high concentration of 2,8 dimethylquinoline, in acetone, adding an equivalent weight of concentrated sulphuric acid to the said acetone solution to precipitate substantially all of the 2,8 dimethylquinoline as an insoluble acid sulphate, leaving the acid sulphates of the admixed non-aromatic bases dissolved in the acetone, removing the insoluble acid sulphate of the aforementioned 2,8 dimethylquinoline from the acetone solution of the acid sulphates of the non-aromatic bases and obtaining the free 2,8 dimethylquinoline by the addition of an inorganic base to the separated acid sulphate of the said 2,8 dimethylquinoline.

12. A process for resolving mixtures of nitrogen bases derived from petroleum, shale and pyrolytic distillates of cottonseed oil, which comprises dissolving said mixtures in an inert organic solvent, forming insoluble acid sulphates of the aromatic bases present in the solution and soluble acid sulphates of the non-aromatic bases present in the solution and separating insoluble acid sulphates of the aromatic bases from the soluble acid sulphates of the non-aromatic bases.

13. A process as defined in claim 1 in which the amount of sulphuric acid added for the production of acid sulphates of the bases is slightly less than an equivalent amount.

14. A process as defined in claim 1 comprising the additional step of cooling the solution of nitrogen bases prior to the addition of sulphuric acid thereto.

JAMES R. BAILEY.
